(57) **CLAIM**

The ornamental design for a footwear outsole, as shown and described.

DESCRIPTION

FIG. 1 is a front perspective view of a footwear outsole showing my new design;

FIG. 2 is a bottom view thereof;

FIG. 3 is a top view thereof;

FIG. 4 is a side view thereof;

FIG. 5 is an opposite side view thereof;

FIG. 6 is a front view thereof; and,

FIG. 7 is a rear view thereof.

The even dashed lines show environmental structure in the form of a footwear midsole and upper that form no part of the claimed design.

1 Claim, 6 Drawing Sheets
